ORCHARD HEATER

Joseph Widman, Los Angeles, Calif.

Application March 12, 1938, Serial No. 195,617

2 Claims. (Cl. 158—91)

This invention relates to orchard heaters and it consists in the constructions, arrangements and combinations herein described and claimed.

- It is an object of the invention to provide a heater of novel construction in which air is admitted to the oil or other fuel and to the combustion chamber in such manner that complete combustion of the fuel is effected, producing an intense heat and elimination of smoke. 10
 10 It is also an object of the invention to provide a novel construction of heater casing which in conjunction with internal parts of the heater function to provide an upwardly flaring flame. 15
 15 It is a still further object of the invention to provide a heater of few parts, which are cheap to construct and readily assembled.

Additional objects, advantages and features of invention will be apparent from the following description considered in conjunction with the 20 accompanying drawings, wherein

Figure 1 is a fragmentary elevational view of a heater constructed in accordance with my invention.

Figure 2 is a cross section on the line 2—2 of Figure 1.

Figure 3 is an elevational view of a modified form of heater, partly in section.

Attention is first invited to Figures 1 and 2 wherein there is shown a heater 10 consisting 30 of a drum 11 of cylindrical form tapering outwardly in the direction of its upper end, but adjacent the latter the wall of the drum is inwardly flared as at 12 to snugly receive an upwardly flared stack 13. The drum 11 and stack 35 may be headed as at 14, for reinforcement.

The lower end of the drum 11 has formed therewith an oil or liquid fuel trough 15. The trough 15 is formed as a continuation of the wall of the drum, the wall being bent horizontally inward as at 16, for a suitable distance, defining a circumscribing flange; thence bent downwardly in a vertical plane defining a wall 17. Continuation of the wall 17 is at an acute angle as indicated at 18 and thence upwardly at an opposite angle for a short distance as at 19, the wall finally terminating in a vertical wall 20. Thus, it will be seen that the trough 15 is formed of substantially V-shape, and it should be noted that the wall 20 stops short of the upper edge of the flange 16 for a purpose presently to be explained. The wall 16 is provided with a multiplicity of staggeredly arranged draft apertures 21, and the wall 17 is similarly provided with apertures 22. The wall of the drum

11 is also provided with apertures 23 opening upon the combustion chamber 24.

In order that the drum may be supported, I provide a base 25 of approved construction to which there is secured a pan 10—a of a size extending beyond the heater 10, and within the pan there are secured crossed leg members 26. The leg members 26, two in number, are formed from sheet strap iron crossed at their medial points, as may be seen in Figure 2. Each strap is bent 10 downwardly as at 27, at opposite sides, forming a vertical portion adapted to snugly abut the wall 20 of the trough. The straps are further bent to provide horizontal portions 29 for support of the trough 15 and these portions extend 15 outwardly to a point in line with circumference of the drum 11, whence the straps are again bent as at 30. Upstanding straps 32 are secured to the strap members at the portions 30 the straps 32 having a foot 31. The upper ends 20 of the straps 32 having an upwardly open loop 33 adapted to receive a circumscribing band 34 fixed to the lower end of the drum 11, and for this purpose the band 34 projects below the drum. 25

Upon the crossed portion of the leg members 26, there is mounted a cup member 35 of a diameter stopping inwardly of the wall 20 of the trough, defining an annular air space 36. The upper edge of the cup 35 is outwardly flared 30 as at 37, stopping approximately in line with the wall 20 of the trough.

In use, liquid fuel will be fed to the trough through the fuel pipe 38, the flow being controlled by means of a float valve as defined in 35 my pending application filed February 21, 1938, Serial No. 191,769.

When fuel has reached a proper level in the trough 15 a small quantity of fuel oil will be poured into the pan 10—a and ignited, pre-heating the fuel oil in the trough 15. Air admitted through the apertures 22 mixes with vapors of the fuel oil forming a highly combustible mixture, the flame from which will be directed outwardly by reason of the flared edge 37 45 of the cup. As the flame increases with consumption of fuel additional air will be drawn rapidly in through the space 36, the apertures 21 and 22, thus supplying the additional air necessary to support combustion. 50

In Figure 3, the drum 11' tapers downwardly its full length to its juncture with the wall of the oil trough, eliminating the flange 16, and also the band 34' is shown spaced from the drum and being secured to the drum by means of an 55

inclined wall 38, which may be welded to the drum at its points of contact therewith. In order that the equivalent amount of air supplied by the aperture 21 may be admitted two pairs of rows of apertures 39 are provided.

5 While I have shown and described preferred forms of the heater, this is by way of illustration only and I consider as my own all such modifications in structure as fairly fall within the scope 10 of the appended claims.

10 I claim:

15 1. An orchard heater comprising a heater drum tapering outwardly in an upward direction, the lower edge of the drum having a circumscribing V-shaped trough integrally formed therewith, the outer wall of the drum having a multiplicity of apertures, a circumscribing band depending from the drum and overlying the apertures, a fuel pan, support members on the pan 20 having upwardly open loops for reception of the band, said support members further having strap members crossed at the vertical axis of the drum, a cup member fixed to the strap members and positioned within the periphery of the trough, 25 the cup member being of a diameter less than

the inner periphery of the trough and defining a circumscribing air space, said cup having an outwardly flared upper edge, the edge overlying the air space, said drum having apertures in the wall thereof above the cup member, and means 5 for feeding fuel to the trough.

2. An orchard heater comprising a drum tapering outward in an upward direction, the lower edge of the drum having a substantially V-shaped annular trough, the outer wall of the drum having a multiplicity of apertures, a circumscribing band depending from the drum and overlying the apertures, a base member having circumferential spaced means cooperable with the band for support of the drum, a cup member carried 10 by the base and disposed within the periphery of the trough, the cup member being of a diameter less than the inner periphery of the trough defining a circumscribing air space, said cup having an outwardly flared upper edge, said edge 15 overlying the air space, said drum having apertures in the wall thereof above the upper edge of the cup member, and means for feeding fuel to the trough.

JOSEPH WIDMAN. 25
